UNITED STATES PATENT OFFICE.

JOHN KELLY, OF NORFOLK, VIRGINIA.

WINDOW DISPLAY APPARATUS.

Application filed July 21, 1919. Serial No. 312,222.

To all whom it may concern:

Be it known that I, JOHN KELLY, a citizen of the United States, residing at Norfolk, in the county of Norfolk and State 5 of Virginia, have invented certain new and useful Improvement in Window Display Apparatus, of which the following is a specification, reference being had therein to the accompanying drawing.

10 This invention relates to improvements in rotary display standards for store windows of the type comprising a standard extending within the window through an opening in the window floor, provided with 15 goods supporting means thereon above the floor, and having a support and motor-driven connection located in the space below the floor of the window.

An object of the present invention is to 20 provide an improved device of the nature referred to, in which the rotary standard with the goods supporting means thereon is adapted to be readily detached from its support and drive connection below the floor 25 and removed from the window, leaving the floor space of the window entirely free for decorating or cleaning purposes, and different goods displays without the use of the rotary display device, the latter being entirely out of the way.

Important novel characteristics of the invention reside in the special construction and arrangement of detachable mounting for the rotary standard, and the special form 35 of support and arrangement of the drive connection relatively thereto resulting in a simple, inexpensive, compact unitary structure that can be conveniently shipped and readily set up in the usual space below the 40 floor of show windows, while at the same time providing a relatively long firm bearing for the standard.

The invention, with other objects and advantages thereof, and the particular construction, combinations and arrangement of parts comprising the same, will be understood from the hereinafter contained detail description when considered in connection with the accompanying drawings forming 50 part thereof and illustrating one embodiment of the invention.

In the drawings:

Figure 1 is a vertical transverse section of a show window equipped with a display 55 device constructed in accordance with the present invention.

Fig. 2 is a detail front elevation of the motor and drive connection.

Fig. 3 is a detail vertical section, on an enlarged scale, of the lower support and drive connection of the display device.

Fig. 4 is a top plan view of the structure illustrated in Fig. 3, with the standard removed therefrom.

While I have illustrated in the drawings 65 a specific embodiment of the invention, it will of course be understood that changes and variations in the particular construction shown, and the carrying out of the invention in other forms, as will appeal to 70 those skilled in the art and falling within the scope of the appended claims, may be made without departing from the spirit of the invention.

In the drawings is illustrated a conventional store window structure comprising glass front 1, ceiling 2, and floor 3. 4 designates the floor below the window floor and 5 the usual space therebetween.

The particular embodiment of the invention illustrated in the drawings includes a support comprising a base part 6, a cup-shaped bearing 7 and a tubular bearing part 8 spaced above and in vertical alignment with the cup bearing 7, a horizontal 80 part 9 connected with vertical arms 10 at opposite sides of the cup bearing 7 carrying the tubular bearing part 8, and on the vertical arms 10 are laterally extending spaced arms 11, the whole being in the form of a 90 single casting of a height less than the distance between the floors 3 and 4 and adapted to rest upon the floor 4 with the tubular bearing part 8 in alignment with an opening 12 in the floor 3 of the window. 13 95 designates an anti-friction ball member in the cup bearing 7. Mounted for rotation in the cup bearing 7 and tubular bearing part 8, with its lower end resting upon the ball 13, is a vertical rotary-driven shaft 100 member 14, the upper end of the shaft member 14 terminating short of the space at the upper side of the window floor, and as shown, preferably extending substantially 105 flush with the upper face of the floor 3. On the shaft member 14 between the cup bearing 7 and the tubular bearing part 8 is a drive gear 14'. In assembling the parts, the shaft member 14 is passed down through the opening 12 in the floor 3 through the 110 tubular bearing part 8, the drive gear 14', and into the cup bearing 7, the drive gear 14'

being fixed on the shaft member 14 by a set screw 14^b. 14^c and 14^d are oil ducts leading respectively to the cup bearing 7 and tubular bearing part 8.

5 Extending vertically within the window is a rotary standard 15 provided with goods supporting means thereon, which, of course, may vary in construction as occasion may require, and in the present showing takes 10 the form of trays or shelves 16 adjustably secured on the standard by the set screws 17. The standard 15 is constructed as a separate part from the shaft member 14, and a quickly detachable supporting and drive 15 connection is provided between said parts whereby the standard can be readily disengaged from the shaft member and removed from the window, leaving the space within the window and its floor entirely 20 free from projecting parts for cleaning, 25 decorating, or like purposes, and for different goods displays which would be hindered by the obstruction presented by the display stand, the latter being entirely out of the way. The connection between the shaft member 14 and the standard 15 is provided by a socket 18 in the shaft member 14 adapted to receive the lower end portion of the standard which extends downwardly 30 through the opening 12 in the floor 3. The lower portion of the standard 15 fits nicely within the socket 18 and while the construction is such as to permit of the ready insertion into and withdrawal of the stand- 35 ard from the socket 18 of the shaft member, at the same time a frictional drive connection between the parts is afforded, so that when the shaft member 14 is rotated rotary motion will be transmitted to the standard 40 15. Any suitable power means and gear connection may be provided for driving the shaft member 14. In the drawings, the drive gear 14' on the shaft 14 is shown as a large worm wheel, meshing with a 45 worm 20 on a horizontal shaft 21 supported in bearings on the laterally extending arms 11. Fixed on one end of the horizontal shaft 21 is a friction disk 22, which is in turn engaged by a friction wheel 23 on one 50 end of the drive shaft 24 of an electric motor 25. The motor 25 has a grooved base 25' slidably mounted on a bed plate 26, the motor being adapted to be shifted along the bed plate to change the position of the drive 55 wheel 23 relative to the friction disk 22 to vary the speed and direction of movement of the shaft member 14. The motor is held in adjusted position by a lock-nut 27 engaging a threaded pin or stem 28 projecting upwardly from the bed plate 26, the motor base 25' having a slot 29 to accommodate the pin 28.

It will be noted that a very simple and practical form of detachable mounting and drive connection for the standard is pro-

vided, and that when the standard is removed from engagement with the shaft member 14 the window floor surface is left entirely free from all obstruction. It will also be observed that the support is in the form of a single casting or unit of compact construction that can be conveniently handled and placed within the usual space below the floors of store windows, while at the same time a relatively long firm bearing is provided for the standard, the removable mounting of the shaft member 14 facilitating the quick assembling of the parts.

What I claim is:

1. The combination with a store window structure including the floor for the window having a vertical opening therethrough, of a support below the window floor, a bearing on the support, a vertically extending rotary driven shaft member supported in said bearing with its upper end terminating below the space at the upper side of the floor of the window, a drive connection for the shaft member located below the floor, and a standard having goods supporting means thereon and adapted to be detachably engaged at its lower end portion with said shaft member to extend vertically therefrom through the opening in the floor of the window above the floor, said standard being adapted to be moved vertically through the opening in the floor to position the same within the window in engagement with the shaft member and to dismount the standard from the shaft member.

2. The combination with a store window structure including the floor for the window having a vertical opening therethrough, of a support in the form of a single casting comprising a base having a cup-shaped bearing, a pair of spaced arms extending upwardly from the base, a horizontal part connecting the said arms and having a tubular bearing part above and in alignment with the cup-shaped bearing, spaced parallel arms extending laterally from the first mentioned arms, a vertically extending rotary driven shaft member supported in the cup-shaped bearing and the tubular bearing part, a gear fixed on the shaft member between the cup-shaped bearing and the tubular bearing part, a rotary horizontal shaft supported in bearings in the laterally extending arms, a gear member on said shaft meshing with the gear on the shaft member, means for driving the horizontal shaft, and a standard having goods supporting means thereon and adapted to be detachably engaged at its lower end portion with the shaft member and to extend vertically therefrom through the opening in the floor of the window above the floor.

3. The combination with a window structure including the floor for the window hav-

ing a vertical opening therethrough, of a support below the window floor, a cup-shaped bearing on the support, a vertically extending rotary driven shaft member re-
5 movably seated in the cup-shaped bearing with its upper end extending substantially flush with the upper face of the floor of the window, a drive connection for the shaft member below the floor, a vertical standard hav-
10 ing goods supporting means thereon remov- ably mounted upon the shaft member to be rotated thereby and extending upwardly through the opening in the floor above the same, said shaft member being provided with a socket, and the standard having a 15 portion at its lower end to fit within the socket and provide a detachable and frictional drive connection between the shaft member and standard.

In testimony whereof I hereunto affix my 20
signature.

JOHN KELLY.
